UNITED STATES PATENT OFFICE.

WILLIAM G. BRITTON, OF FANWOOD, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,296,617.

Specification of Letters Patent. Patented Mar. 11, 1919.

Application filed July 29, 1916. Serial No. 112,030.

To all whom it may concern:

Be it known that I, WILLIAM G. BRITTON, a citizen of the United States, residing at Fanwood, in the county of Union and State of New Jersey, have invented certain new and useful Improvements in Telephone Systems, of which the following is a full, clear, concise, and exact description.

This invention relates to telephone systems, and more particularly to that class of such systems generally known as paging or announcing systems.

Generally stated, one of the objects of this invention is the provision of a telephone system which is very flexible from the standpoint of the number of annunciators that may be operated and the ability to severally and collectively regulate the volume of sound produced thereby.

Another object is the provision of a system of the above type in which the number of relays is very low.

A further object of this invention is the provision of means whereby it is possible to selectively operate various groups of annunciators and accomplish this feature without the necessity of having direct current pass through the devices effecting the selection.

In accordance with this invention, there is provided a plurality of transmitting stations, from each of which it is possible to selectively operate a group or groups of amplifiers, which in turn actuate groups of loud speaking receivers. The amplifiers are normally not included in the transmission circuit, but are adapted to be inserted therein through the agency of selecting keys. To prevent any irregularity in the volume of sound produced by any given receiver due

to the varying of the resistance in the transmission circuit which would result by varying the number of amplifiers selectively placed therein, compensating means, preferably located at the transmitting stations, function to regulate the strength of the energizing current for actuating the amplifiers so that the volume of sound produced by the receivers controlled by a given amplifier remains constant. The selecting keys are placed in the circuit organization of the sending station in such a manner that the current for energizing the transmitter does not pass through the contacts of said keys.

The system, normally inactive, is rendered effective by the actuation of a single switch-

ing element. Other features will be apparent from the description hereinafter given.

The invention is illustrated in the accompanying drawings, in which Figures 1 and 2, taken together, diagrammatically represent an entire system, Fig. 1 being a circuit diagram showing a plurality of transmitting stations contemplated by this invention, and Fig. 2 showing the organization of the apparatus designed to be controlled by such transmitting stations.

The transmitter circuit of each of the transmitting stations A, B and C shown in Fig. 1 includes a transmitter 1, condenser 2, the primary winding of an induction coil 3, 70 and a non-locking key 4, arranged in the circuit as shown. The key 4, besides controlling this transmitter circuit, also controls an energizing circuit for signals 5, one signal being located at each transmitting station, 75 which are adapted to give a busy indication at all stations when any of the keys 4 are operated. Placed in the secondary circuit of induction coil 3 are a plurality of selecting keys 6, 7, 8, 9 and 10, preferably of the well-known locking type, which control the 80 circuits of a series of compensating resistances 11, 12, 13, 14, and 15 respectively, these resistances being normally inductively connected with the circuit of the transmitter 1 85 as shown. Key 4 also controls a contact piece 16, which is adapted to close the several circuits of the compensating resistances when the key is in an actuated position. Conductors from the transmitting stations 90 A, B and C terminate in a panel board, represented by the dotted lines in Figs. 1 and 2, to which is led the terminals from a suitable source of current for actuating the amplifying and other apparatus. 95

In Fig. 2 there is shown a plurality of amplifiers 20, which may be similar in construction to that forming the subject matter of a patent to Henry C. Egerton, No. 1,207,384, dated December 5, 1916. Briefly, the amplifiers 20 comprise a transmitter element of the well-known "push and pull" or differential type wherein two transmitter buttons are customarily used and connected with a vibrating medium in such a way that an increase in the resistance of one button is accompanied by a simultaneous decrease in the resistance of the other. The magnet system of the amplifiers schematically 105 illustrated in the drawing embodies a mag- 110

netizing winding 40 wound about an iron core and arranged to magnetize the ends thereof to the same polarity. An actuating winding 41, which receives the current to be amplified, is disposed so as to operate a vibrating armature 42 which effects the operation of the transmitter buttons 43. The transmitter elements or buttons 43 of each amplifier 20 are associated with the output circuit by being connected to the primary winding of an induction coil 21, the secondary winding of which is connected to outgoing line conductors as shown. The amplifiers 20 are preferably arranged in groups, the number of such groups corresponding to the number of selecting keys located at the transmitting station. The number of amplifiers comprising the several groups may be varied as desired. In accordance with approved telephone practice, there is associated with each of the various groups of amplifiers a protective device 22 and a high impedance coil 23, whose functions are well understood in the art. The circuit organization of the elements just described is schematically represented in the upper part of Fig. 2. Each of the output circuits of the various amplifiers 20 may include one or more loud-speaking receivers 24 of the usual construction, which are connected in multiple when a plurality is employed. If the effective output of all of the amplifiers is substantially equal, it is possible, with the particular circuit arrangement of this invention, to vary the volume of sound produced by the respective receivers of a given group. In other words, if one amplifier carries two receivers while another carries four, the volume of each of the two receivers will be considerably greater than that of each of the four receivers. It will be apparent that such an arrangement is advantageous where it is desired to furnish paging service in rooms of different sizes or where, in some locations, there are apt to be disturbing noises, while other rooms are more or less quiet.

The paging system embodying this invention will be fully understood from a description of its operation. A party wishing to transmit a message from any of the stations A, B and C may first selectively close the desired combination of selecting keys 6 to 10 and then operate the key 4. Let it be assumed that the message is to be transmitted from station A. The operation of the key 4 effects the closure of a plurality of circuits, one of which, extending from the positive side of the switch 25 located on the panel board through conductor 26, key 4, transmitter 1, conductor 27, resistance 28, and back to the negative side of switch 25, supplies talking current for transmitter 1. A second circuit completed by the actuation 65 of the key 4 effects the operation of the

"home" busy signal 5, the circuit for which extends from battery at one side of switch 25, conductor 26, key 4, winding of signal 5, conductor 29, resistance 30, through the switch 25 to the other side of battery. 70 Simultaneously with the completion of the circuit for the signal 5 located at transmitting station A, a corresponding circuit is closed for the signal at station B which may be traced from the positive side of battery at switch 25 through conductor 26, key 4 of station A, conductors 45 and 46, winding of signal 5, conductor 47 and resistance 30, to the negative side of battery at switch 25. In a similar manner a circuit is established 75 for signal 5 located at station C. The display of the signals 5 at the stations B and C indicate to a person desirous of transmitting a message from one of those stations that the system is already in use. In addition, 80 the magnetizing windings 40 of all of the amplifiers 20, are energized upon the operation of the key 4. The energizing circuits thus provided may be traced from the positive side of battery at switch 25, through 85 conductor 26, key 4, conductors 45 and 48 through all of the magnetizing windings 40 of the amplifiers (which, as shown, are connected in parallel in groups of four in series) conductors 49 and 53, to the negative 90 side of battery at switch 25. From the foregoing it will be seen that the operation of the switch 4 accomplishes three distinct results which may be epitomized as follows: First, current is supplied to the transmitter 100 1; second, the operation of all of the busy signals 5 is effected; and third, magnetizing current is connected to all of the corresponding amplifiers 20.

Another circuit closed by the operation of the key 4 inductively connects the compensating resistances 11, 12, 13, 14 and 15 in the transmission circuit, through the medium of the secondary winding of the induction coil 3. It may be mentioned here that each of the compensating resistances 11, 12, 13, 14 and 15 shown at the respective transmitting stations represent approximately the total resistance of the same number of amplifiers 20 as controlled by a corresponding 110 one of the selecting keys 6, 7, 8, 9 and 10, to which said resistances are connected. For example, if selecting key 6 is operated, it places in the circuit the first three of the amplifiers 20 which may be designated as 115 50, 51, and 52, which in turn operate nine of the receivers 24 allotted to group D. If, however, the selecting key 6 is in the normal position, as shown, the three amplifiers 50, 51, and 52 are disconnected from the transmitting circuit and the compensating resistance 11, which represents the combined resistance of these three amplifiers, is connected with the talking circuit instead. By thus keeping the resistance in the transmis- 120 125 130

sion circuit substantially constant, the volume of sound produced by a given one of the loud-speaking receivers remains substantially the same at all times, regardless of 5 whether one or more of the receiver groups D, E, F, G, H are being operated. Another feature that may be noted at this point is that by the arrangement of the secondary circuit of each of the transmitting stations 10 A, B and C, the operation of one of said stations is entirely independent of the others, and when a station is not in use, its secondary circuit is disconnected by means of a key 4. This arrangement avoids the 15 necessity of having to set the keys 6, 7, 8, 9 and 10 in a required position after announcing has been made in order not to interfere with the operation of the system from any other transmitting station. Consequently, 20 from the standpoint of operation, it is immaterial what position the keys 6, 7, 8, 9 and 10 of the respective stations A, B and C occupy when not in use.

Assume, for the sake of illustration, that 25 the selecting key 6 is operated by the party at the transmitting station A. The operation of the key 6 opens contact 17 and closes contact 18, thereby substituting the amplifiers for operating the receivers 24 comprising group D for the compensating resistance 11. The circuit established by this operation may be traced from contact 18 of key 6, conductor 33, contact 34, conductor 35, secondary winding of induction coil 3, conductor 36, through the actuating windings 41 of each of the amplifiers 50, 51, and 52, conductor 37, back to contact 18. The closure of this circuit places the amplifiers 50, 51, and 52 in a condition to be agitated by 30 voice currents. The current generated in the actuating winding of each of the amplifiers 50, 51 and 52 operates their respective armatures 42 which in turn causes variations in the current passing through the primary winding of each of the induction coils 21 connected in the respective circuits of these amplifiers. From the secondary winding of these induction coils the energizing current is conveyed for operating the loud-speaking receivers 24. It will be noted that 45 in group D the amplifier 50 carries four of the receivers 24, amplifier 51 carries two, while amplifier 52 carries three, and, as the effective output of each of said amplifiers 50 is preferably substantially equal, the volume of sound produced by the receivers 24 is varied by virtue of this arrangement.

It will be apparent from the above description that the number of receivers associated with any particular amplifier may be 50 changed at any time to meet existing or changed conditions by increasing or decreasing the number of receivers associated with such amplifier. Such change results in altering 55 the relative volume of sound produced

by each of the receivers associated with the particular amplifier concerned, but is otherwise without effect upon the system; thus providing for independent adjustment of each group of receivers without derangement of other receiver groups or other apparatus of the system.

In case the selecting key 7 has been operated instead of key 6, four of the amplifiers 20 would have been placed in the transmission circuit, these amplifiers in turn actuating the loud-speaking receivers 24 forming group E. By operating keys 8, 9 and 10, groups of receivers F, G and H, respectively, may be actuated. From the above it 75 is obvious that any or all of the groups of receivers may be operated from any of the transmitting stations by the operation of the selecting keys controlling their introduction 80 into the transmission circuit.

From the above it will be apparent that the paging system contemplated by this invention is characterized by its elasticity both from the standpoint of the number of loud-speaking receivers that may be operated at a given time and the possibility of varying the respective volumes thereof. Another prominent feature is the absence of 90 relays or equivalent electromagnetic switching devices usually found in a paging system having the flexibility of the one in question.

While the preferred embodiment of this invention is herein shown and particularly described, it is not intended to be limited to 100 the precise details of the circuit organization illustrated, as changes may readily be made without departing from the spirit of the invention.

What is claimed is:

1. A telephone system including a plurality of transmitting stations, amplifiers, means adapted to actively associate any station with independent predetermined groups of said amplifiers, and compensators 110 controlled by said means for maintaining the output of said amplifiers substantially constant.

2. A telephone system including a transmitting station, amplifiers, circuits adapted to selectively associate the amplifiers with said station, compensating resistances, and means for effecting the interchanging of said amplifiers and said resistances in a given circuit.

3. A telephone system including a transmitting station, amplifiers, means adapted to actively associate said station with independent predetermined groups of said amplifiers, and compensating resistances normally in an energizing circuit for said amplifiers but arranged to be removed therefrom for maintaining the output of the amplifiers substantially constant.

4. A telephone system including a trans-

mitting station, the transmission circuit of said station including the primary winding of an induction coil, compensating resistances adapted to be associated with the secondary winding of said induction coil, amplifiers, and means for substituting said amplifiers for said resistances in said secondary circuit.

5. A telephone system including a plurality of transmitting stations, amplifiers,

loud-speaking receivers connected to said amplifiers, said amplifiers and receivers being arranged in associated predetermined groups, and selectable manually actuated means at each of said transmitting stations 15 for directly telephonically connecting any of said groups with said transmitting station.

In witness whereof, I hereunto subscribe my name this 28th day of July, A. D., 1916.

WILLIAM G. BRITTON.
